UNITED STATES PATENT OFFICE.

PASQUALE A. RICCIO, OF BROOKLYN, NEW YORK.

FUSE.

1,355,779.

Specification of Letters Patent.

Patented Oct. 12, 1920.

Application filed April 2, 1919. Serial No. 286,967.

To all whom it may concern:

Be it known that I, PASQUALE A. RICCIO, a citizen of the United States, and a resident of the city of New York, borough of Brooklyn, in the county of Kings and State of New York, have invented a new and Improved Fuse, of which the following is a full, clear, and exact description.

This invention relates to fuses, and aims 10 to provide a device of this nature which may primarily be handled by absolutely inexperienced operators without any danger of the fingers being burned upon the insertion of such fuse into the conventional clips.

15 A further object of the invention is to provide a fuse which incorporates construction eliminating the necessity for fuse switches, in that the fuse itself incorporates a switch feed.

20 Another object of the invention is the provision of a fuse which will permit of the renewal of the fusible material at a far less cost than for the fuses of the renewal type now upon the market.

25 A final object is the provision of a fuse in which the most inexperienced operator can immediately find out as to whether the same has been "blown" or not.

Reference is had to the accompanying 30 drawings which illustrate one practical embodiment of my invention, and in which—

Figure 1 is an elevational view of my improved form of fuse;

Fig. 2 is an end view of the fuse as illustrated in Fig. 1 showing the same embraced by conventional fuse clips;

Fig. 3 is a side elevation, partly in section, of a fuse having the same general characteristics of the device illustrated in 40 Figs. 1 and 2 but being slightly modified so as to be more particularly adapted for use in connection with high amperage circuits; and

Fig. 4 is a section taken along the lines 45 A—A of Fig. 2.

In these drawings the reference numeral 1 designates the outer body or casing of fiber, rubber, or any other suitable insulating material, which body is provided with 50 two notches at each of its upper and lower ends, which notches are preferably located at diametrically-opposite points in the circumference of the casing. Mounted in the ends of the casing 1 are caps 3 of metal provided with integral lugs 4, which lugs are 55 adapted to project through the notches

2 and to be bent downwardly at right angles so as to lie against the side walls of the casing 1. The ends of such lugs 4 are preferably prong shape, as shown at 5, such prongs being projected inwardly into the body of the casing 1, so that any displacement of the caps 3 is effectually prevented.

Considering now the device illustrated in Fig. 4, it will be seen that the cap 3 is provided with a screw-threaded opening in which is mounted a screw 5. A further opening 6 extends through the cap 3, and projecting through such opening and extending between the upper and lower caps 70 3 is a fusible wire 7 whose ends, as aforesaid, project through the opening 6, subsequent to which the end is wound around, as shown in Fig. 2, the screw 5. A disk 8, of any suitable material, is mounted around 75 the screw 5, and upon such screw being tightened the wire 7 will be firmly clamped in position between the lower face of the disk 8 and the upper face of the cap 3.

It will be appreciated by those conversant 80 with fuse construction, that although the device illustrated in Fig. 4 might operate well enough on a low amperage circuit, upon the wire 7 fusing a terrific heat would be set up in the casing 1, which heat might 85 result in the mutilating of the threads of the screw 5, which would render it extremely difficult to rotate such screw so that a replacement of the wire 7 might be effected. To overcome this, I have slightly 90 modified the cap 3, as illustrated in Fig. 3, by securing, in any suitable manner, a plug 9 of any material to the underside of the cap 3; and I have extended the screw-threaded opening in which the screw 5 seats 95 into such plug 9 in the form of a socket, so that the screw threads upon the plug 5 will not be exposed to any flame upon the wire 7 fusing, and, consequently, it will be impossible for injury to result to the screw 100 threads upon the screw 5.

In operation it will now be seen that the fuse is inserted into the clips of a conventional fuse block as has been illustrated in Fig. 2, with the lugs 4 in contact with the 105 spring clips. To determine as to whether the fuse is still in good condition, all that it is necessary to do is for the operator to turn one of the fuses so that the lugs 4 almost contact with the spring clips of the 110 fuse block. Assuming now that the feeder fuse has not been blown and that there is

a load upon the circuit, if a sparking does not result the fuse is dead, or else the line in which the same is interposed is grounded.

It will be appreciated that by this method of insertion, all danger of sparking, such as occurs in the usual fuse upon its insertion into the clips of a block, is eliminated by virtue of the fact that no circuit is established through the fuse, even although the same may be seated in the clips, until the body and, consequently, the lugs 4, have been rotated so that such lugs are engaged by the spring clips. It will further be appreciated that by this rotational movement, the fuse may be used as a switch, as the circuit will be entirely broken every time the fuse is rotated.

It will be understood that by the arrangement of the fusible wire, such wire may readily be renewed, should the same become burned out, and it will also be understood that the cost of such renewal will run far less than the cost of renewals in fuses now upon the market.

Having thus described my invention, I claim as new and desire to secure by Letters Patent:

1. A fuse including a body portion, a fusible element within such body portion, contact surfaces attached to the ends of said fusible element, said body portion being adapted to be applied to and retained by conventional fuse clips, the contact surfaces thereof bearing against said clips, such body being adapted to be moved whereby to disengage the clips and contact surfaces without removal of such fuse from said clips whereby said fuse is adapted to serve as a switch.

2. A fuse including a body portion, a fusible element within said body portion, contact surfaces arranged upon the outer face of, adjacent the ends of said body portion, and being disposed at points diametrically opposite to one another, said contact surfaces being secured to the ends of said fusible element and bearing against conventional fuse clips which serve to retain said fuse in applied position, said fuse serving as a switch upon the rotation of said body portion, which causes a disengagement of the contact surfaces and clips.

3. A fuse, including a cylindrical body of insulating material, notches formed in the upper and lower edges of such body, caps mounted in the upper and lower ends of

the body and having certain of their portions projecting through such notches whereby to provide contact points, and current-conducting means extending between 60 such caps.

4. A fuse, including a cylindrical body of insulating material having notches formed at diametrically-opposite points in its upper and lower edges, caps mounted 65 within its upper and lower ends, certain portions of such caps extending through the notches whereby to provide contact points, and current-conducting means extending between such caps. 70

5. A fuse, including a cylindrical body of insulating material provided with notches in its upper and lower edges, caps mounted in its upper and lower ends, such caps being formed with lugs adapted to extend outwardly through the notches and downwardly along the sides of the fuse, whereby to provide contact points, and current-conducting means extending between such caps. 75

6. A fuse, including a cylindrical body of insulating material provided with notches in its upper and lower edges, caps mounted in its upper and lower ends, such caps being formed with lugs adapted to extend 85 outwardly through the notches and downwardly along the sides of the fuse and having their ends prong shaped and extending into the outer face of the body, and current-conducting means extending between 90 such caps.

7. A fuse, including a body of insulating material, caps mounted in the upper and lower ends of such body, fusible wire extending between such caps, screws projecting through such caps and being adapted to retain in applied position the ends of the wire, and means connected with such caps for protecting the base of the screws. 95

8. A fuse, including a body of insulating material, caps mounted in the upper and lower ends of such body, fusible wire extending between such caps, screws projecting through such caps and being adapted to retain in applied position the ends of the wire, and means connected with such caps for protecting the base of the screws, such means including a plug formed with a socket 100 alining with the end of the screw and being secured to the underside of the cap. 110

PASQUALE A. RICCIO.
